G. J. Champaine

UNITED STATES PATENT OFFICE.

GEORGE J. CHAMPANE, OF BEACHMONT, MASSACHUSETTS.

DESIGN FOR A SOUNDING-POST TOOL.

55,365.

Specification for Design.

Patented June 1, 1920.

Application filed March 1, 1920. Serial No. 362,562. Term of patent 3½ years.

To all whom it may concern:

Be it known that I, GEORGE J. CHAMPANE, a citizen of the United States, residing at Beachmont, in the county of Suffolk and State of Massachusetts, have invented a new, original, and ornamental Design for a Sounding-Post Tool, of which the following is a specification, reference being had to the accompanying drawing, forming part thereof.

Figure 1 is a perspective view of a sounding post tool showing my new design,

Fig. 2 is a side view of the sounding post tool of Fig. 1.

I claim:—

The ornamental design for a sounding post tool, as shown.

GEORGE J. CHAMPANE.
